UNITED STATES PATENT OFFICE.

JEFFERSON HERKS, OF DETROIT, MICHIGAN.

CIGAR HOLDER.

Application filed December 5, 1922. Serial No. 605,023.

To all whom it may concern:

Be it known that I, JEFFERSON HERKS, a citizen of the United States, residing at Detroit, in the county of Wayne and the State of Michigan, have invented certain new and useful Improvements in Cigar Holders, of which the following is a specification.

This invention relates to a holder designed to act as a carrier case for a cigar, preventing the same from being broken, it also acts as a holder for a lighted cigar when entering any place where smoking is prohibited, the cigar when so enclosed going out, and a portion of it may also be used as a mouth piece or holder when smoking.

The main object of the invention is to provide a carrier for a cigar that has been lighted and which the owner does not wish to throw away, but wishes to re-light and continue smoking at some future time, as for example after coming from a theatre or other building where smoking or the open carrying of a lighted cigar is prohibited.

With the above objects in view the invention consists of the following novel features, pointed out in the claim and shown in the accompanying drawing, in which:

Figure 1 is a vertical section showing the mouth piece detached from the holder and the cigar partly inserted.

Figure 2 is a longitudinal section showing the cigar enclosed.

Figure 3 is a cross section on the line 3-3 of Fig. 2.

In the drawing 1 is a cylindrical body portion formed of any suitable material. A mouth piece and cigar holder 2 of the usual type is adapted to be threaded into one end of said holder or body portion. To the opposite end of the body is threaded a bottom or end portion 3. This may be removed and the ashes knocked from the cigar before resuming smoking. Within the body portion and secured to opposite

side walls of the same, and extending substantially parallel to each other and to the axis of the body are springs 4.

At their free ends these springs carry cuffs or clips 5 adapted to grip and partially embrace the cigar and to hold the same away from the walls of the holder. This not only prevents the walls from becoming heated or in contact with the lighted portion of the cigar, but prevents movement of the cigar in the holder which might break the wrapper. Opposite the springs the holder is suitably apertured and pins 6 secured to the springs pass through said apertures, which are sufficiently long to permit play of the pins, and said pins carry heads 7. The springs cause the cuffs 5 to grip the cigar and also draw the heads 7 to the holder closing the apertures. A cigar so enclosed will be quickly extinguished. By removing the bottom portion 3 the ashes can be knocked off before withdrawing the cigar from the holder.

To release the cigar the thumb and forefinger are pressed against the heads 7 pressing them into the position shown in Figure 1. This separates the springs and releasing the cuffs or clips, and the cigar can then be easily withdrawn, and smoked either with or without the holder tip 2.

What I claim is:—

A holder of the kind described comprising a body portion, a mouth piece detachably carried by one end of the body portion, springs arranged within the body portion, clips carried by the springs adapted to embrace a cigar, and headed pins extending through the wall of the body portion and secured to said springs, pressure upon the pin heads spreading the springs and releasing the clip.

In testimony whereof I affix my signature.

JEFFERSON HERKS.
